HEAT EXCHANGER

Otto Hartmann, Kassel-Wilhelmshohe, Germany

Application March 1, 1940, Serial No. 321,757
In Germany May 19, 1939

3 Claims. (Cl. 257—239)

This invention relates to an indirectly heated heat exchanger, for instance a steam generator or the like, the heating elements of which are arranged within a drum in such a manner that they can be inserted into the drum and withdrawn from the drum through the man-hole of the same. The connection of these heating elements with the conduits for supplying and withdrawing the heating medium or the heated agent is effected by means of special headers within the drum, portions of the headers extending through the wall of the drum and communicating at the one end with said conduits. The remaining portions of the headers have distribution chambers and collecting chambers arranged within the drum to which the heating elements are attached.

The invention presents a solution of the problem by designing the heating elements in such a manner that an individual element does not exceed the dimension of the major axis of the man-hole of the customary size so that every element can be introduced into the drum and withdrawn from the same through a man-hole of the usual size. Accordingly the headers, including the distribution chambers and the collecting chambers with which the heating elements communicate, are subdivided in their vertical direction, and the inner spaces of the superposed part chambers are connected with one another by rolled socket pieces or the like. Making use of headers designed according to this invention makes it possible to choose the height of the headers in such a way that the customary length of the major axis of the man-hole is not exceeded.

The number of heating elements so dimensioned is not limited to only one in a vertical plane of the drum, but a plurality of such elements may be arranged one above the other. The individual header chambers of the superposed elements can be connected with one another by means of rolled sockets or joining pieces which, after the elements have been introduced into the drum, are inserted into the chambers and rolled fast. In order to withdraw the elements from the drum the relatively short sockets or pieces are cut, whereafter the elements can be individually withdrawn through the man-hole in spite of the restricted size of the same.

The division of the interior of the individual headers into chambers reduces the number of the openings through the drum wall. It is, furthermore, a particular feature of the invention that the heating elements, owing to their small dimensions, can be assembled in a compact manner, both with regard to their base area and their

height, whereby the interior of the drum is provided with large heating surfaces.

A point worth mentioning is that the manufacture of drums with manholes of normal size is simpler and cheaper than if the man-holes are to be of an exceedingly large size, as was usual up to the present time in order to allow of the insertion of the heating elements. The two last-mentioned advantages also enable the use of the normal or standard small drums in the case of the indirect generation of steam, in consequence whereof the respective boilers can likewise be manufactured more cheaply.

The invention is illustrated diagrammatically and by way of example on the accompanying drawing on which Figure 1 is a vertical longitudinal section through a drum with heating elements designed according to this invention; Figure 2 is a horizontal longitudinal section through the same; Figure 3 is a transverse section in the plane III—III of Fig. 1; Figure 4 shows a vertical longitudinal section through two superposed header units including the collecting chambers, these parts being drawn to an enlarged scale relatively to Figs. 1 and 2; and Figure 5 is a section on the line V—V of Fig. 4.

On the drawing, 1 (Figs. 1-3) denotes the drum which may be the upper drum of a steam generator; the drum is partly filled with water to be transformed into working steam. The tubes 2 have the shape of hairpins, of which there are many arranged in vertical and in horizontal series, as appears from Figs. 1 and 2. The ends of the tubular heating elements 2 are firmly connected to their respective headers, each of which is composed of distributing chambers 3 and collecting chambers 4 (Fig. 4). In each unit, chamber 3 is separated from chamber 4 by partitions 5. There are, in the example in question, two header units arranged above one another and connected with one another by short tubular members 6 formed, for example, by pieces of drawn tube. The upper ends of the chambers in the uppermost header units are closed by drawn metal plugs 7. The pieces of tube 6 are preferably secured in place by rolling; the tool for effecting this can be introduced into the upper ends of chambers 3 and 4 prior to the insertion of the stoppers 7.

The lower header is provided with a projection 10 which extends outwardly through the wall of the drum and contains a partition wall 11 forming a continuation of the partition wall 5 of said unit. Between this latter and the projection 10 is a shoulder 12 located upon a pack-

ing ring 13 (Fig. 4). At the outer end of the projection 10 is a flange 14 for connecting the headers to the respective pipes supplying the heat-carrier, or the heat transmitting and supplying agent, especially steam, and for discharging that agent, or the condensed steam, when it escapes from the chambers 4. 8 (Fig. 1) denotes the first-mentioned pipes and 9 denotes the other ones. The ends of these pipes are secured to a common flange-like body 16 having 10 suitable passages for establishing communication between the pipes 8 and the chambers 3, and between the pipes 9 and the chambers 4. The body 16 is connected with the flange 14 by bolts 15 extending upwardly into this flange and 15 provided with counter-nuts 17, as clearly shown in Fig. 1. The bolts 15 press onto the outer surface of the drum and draw the header units against the packing ring 13 by the intermediary of the shoulder 12, and the nuts 17 press the 20 body 16 against the flange 14 whereby all these members are firmly connected with one another and tightly sealed to one another.

The height of any one of the header units corresponds substantially with the major axis 25 of the man-hole 18 provided in one of the frontal walls of the drum. A plurality of the headers are arranged side by side (Fig. 3) and two or more of the headers are superimposed upon each other. I wish it, however, to be understood that I do not limit myself to merely two superposed units, as in Figs. 1 and 4, as more than two may be arranged in the above-described manner. If 30 the headers and tube elements are to be removed from the drum, the connecting pieces 6 are cut through, whereafter it is at once possible to withdraw every tube bundle and the header unit to which it is attached through the man-hole 18.

From Figs. 1 and 4 it is seen that the pipes 2 of adjacent headers are staggered relatively to one another, as is the case also with the pipes 8 and 9 with respect to the connecting bodies 16. From Figs. 1 and 2 it is seen, furthermore, that the interior of the drum is filled with heat- 40

ing elements, or with pipes 2 respectively, to the utmost degree. This is rendered possible only by the particular arrangement and combination of the various members constituting the tubes and header units, especially by the particular manner of subdividing the header units into chambers 3 and 4. Separate holes for each chamber are not needed in the wall of the drum. As such holes would reduce the strength of the wall, a greater wall thickness and consequently a heavier drum would result. These drawbacks are obviated in the simplest manner by the superposition of the divided header units and by the connection of the same by means of the tubular sockets, as described.

I wish it to be understood that my invention is not limited to the details of the constructional form shown merely by way of example. Departures are possible remaining fully within the scope of the invention and the annexed claims.

I claim:

1. A heat exchanger for an indirect steam generating system comprising a drum, a manhole in one end of said drum, a plurality of header units each of which has its major dimension less than the major axis of said manhole and each of which is subdivided into a distributing chamber and a collecting chamber, said units being mounted in rows transversely of said drum with at least one unit superimposed upon another unit and with the respective chambers thereof vertically aligned, separable joints connecting the superimposed units, and tube bundles horizontally extending in said drum and joined to their respective header units.

2. A heat exchanger as in claim 1, said separable joints comprising severable tubes telescoped within the aligned chambers of adjacent units.

3. A heat exchanger as in claim 1, the lowermost of each of said superimposed units being mounted to project through the wall of said drum, and means for supplying the projecting ends of said units with a heating medium.

OTTO HARTMANN.
